[57] CLAIM

The ornamental design for a combination cheese grater and container, as shown and described.

DESCRIPTION

FIG. 1 is a perspective view of a combination cheese grater and container showing my new design;

FIG. 2 is a front elevational view thereof;

FIG. 3 is a rear elevational view thereof;

FIG. 4 is a side elevational view thereof, the side opposite being a mirror image of the side shown in FIG. 4.

FIG. 5 is a top plan view thereof; and,

FIG. 6 is a bottom view thereof.

The article shown is in a closed position in FIGS. 2-6 for clarity of illustration.

FIG. 1

FIG. 2

FIG. 3
